(57) **CLAIM**

The ornamental design for a charging holder for a sphygmomanometers, as shown and described.

DESCRIPTION

1. Charging holder for sphygmomanometers

1.1 : Perspective

1.2 : Front

1.3 : Back

1.4 : Left

1.5 : Right

1.6 : Top

1.7 : Bottom

1.8 : Other side perspective
